[57] CLAIM

The ornamental design for a handle for luggage or the like, substantially as shown and described.

DESCRIPTION

FIG. 1 is a perspective view of a handle for luggage or the like showing our new design;

FIG. 2 is a front elevational view thereof;

FIG. 3 is a top plan view thereof;

FIG. 4 is a bottom plan view thereof; and

FIG. 5 is an end elevational view thereof, the opposite end being substantially a mirror image thereof.

FIG. 1

FIG. 3

FIG. 2

FIG. 5

FIG. 4
